UNITED STATES PATENT OFFICE.

JOSEPH G. HUTCHINSON, OF ATTLEBOROUGH, MASSACHUSETTS.

DESIGN FOR A DISPLAY SHOW-CASE.

SPECIFICATION forming part of Design No. 32,980, dated July 24, 1900.

Application filed November 13, 1899. Serial No. 736,883. Term of patent 3½ years.

To all whom it may concern:

Be it known that I, JOSEPH G. HUTCHINSON, a citizen of the United States, residing at Attleborough, in the county of Bristol and State of Massachusetts, have invented and produced a new and original Design for a Display Show-Case, of which the following is a specification, reference being had to the accompanying drawings, forming a part thereof.

Figure 1 is a side elevation of a display show-case, showing my new design; and Fig. 2 is a perspective view of the same, these views being deemed necessary to fully illustrate my design.

My design consists of a display show-case having a circular concavous base, a standard extending upward from the central portion of said base, a circular concavous tray surmounting said standard and having an outwardly-curved peripheral side and raised radial ribs arranged and disposed as shown in Fig. 2, said ribs forming sector-shaped recep-

tacles, and a circular disk with a knob post extending upward from the center thereof.

In the drawings, A represents the base of 25 the display show-case. B represents the standard extending upward from the center of said base, and C represents the circular concavous tray surmounting said standard and having the radial ribs a a, forming the 30 sector-shaped receptacles b b, and d represents the disk having the concentric knob-post.

Having described my invention, what I claim as new, and desire to secure by Letters Patent, is—

35

The design for a display show-case as herein shown and described.

In testimony whereof I have signed my name to this specification in the presence of two subscribing witnesses.

JOSEPH G. HUTCHINSON.
